UNITED STATES PATENT OFFICE.

ALBERT C. KAUFMANN, OF CINCINNATI, OHIO.

ATTACHMENT FOR HEADLIGHTS.

1,152,182.

Specification of Letters Patent. Patented Aug. 31, 1915.

Application filed August 26, 1914. Serial No. 852,701.

To all whom it may concern:

Be it known that I, ALBERT C. KAUFMANN, a citizen of the United States, residing at Cincinnati, in the county of Hamilton and State of Ohio, have invented certain new and useful Improvements in Attachments for Headlights; and I do hereby declare the following to be a full, clear, and exact description of the invention, such as will enable others skilled in the art to which it appertains to make and use the same.

This invention relates to new and useful improvements in attachments for head lights, and has for its principal object to provide a device which will effectively shade a head light to prevent the same from shining in the eyes of pedestrians or others using the roadway upon which the vehicle carrying the head light is traveling.

Another object of the invention is to provide a pivoted shield which may be operated from the seat of the driver without necessitating any change of position.

A further object of the invention is to provide a simple and effective device which may be made of any suitable sheet material and which will effectively protect the eyes of persons approaching the vehicle upon which the device is used.

With these and other objects in view, the invention consists in the novel combination and arrangement of parts which will be fully set forth in the following specification and accompanying drawings in which:

Figure 1 is a side view in elevation of a head light showing the shield in place thereon in its operative position, Fig. 2 is a front view of Fig. 1, Fig. 3 is a side view in elevation of a head light showing a modified form of shield as it would appear when in place, and Fig. 4 is a front view in elevation of the Fig. 3.

Referring now to the drawings by characters of reference, the numeral 1 designates as an entirety the head light of the ordinary construction carrying the usual socket 2 by means of which the light is supported. Secured at diametrically opposite points of the head 3 in which the lamp 4 is carried, are the brackets 5, which form stops to limit the downward movement of the shield. A similar stop 6 is secured to the lamp 1 near its rear end and is arranged to limit the shield in its rearward movement when swung on its pivot.

The shield hereinbefore referred to, is designated generally by the numeral 7 and comprises an oblong body portion 8 having formed at each end the triangular members 9. One of these triangular members is provided with an integral depending arm 10, the lower end of which is pivotally connected as at 11 to the rod 12, which extends rearwardly of the vehicle and forms the controlling means. The triangular members 9 are bent angularly as illustrated in the drawings and the free ends of the triangular members are pivotally secured as at 13 to the lamp 1, thus hingedly securing the shield in place.

In the use of the shield hereinbefore described, the same is pivoted to the lamp as illustrated by the numeral 13, and upon shifting the rod 12 forwardly or rearwardly, it will be apparent that the shield will be raised or lowered and will engage the stops 5 and 6, and thus limit the movement of the shield.

In the modified form of the invention, which is best illustrated in Figs. 3 and 4, the main portions of the lamp are designated by the numerals used in Figs. 1 and 2, but the shield is designated generally by the numeral 14. This shield comprises the oval body portion 15 having formed at each end the extensions 16. These extensions are pivotally secured as at 17 to the lamp 1 and have formed integral therewith the reduced extensions 18 which are pivotally secured as at 19 to the operating rod 20, which extends rearwardly of the vehicle and forms the operating means whereby the shield may be controlled.

In the modified form of the invention it will be apparent that the main body portion 15 of the shield lies so that its upper edge conforms to the curvature of the inner edge of the head 3 and the lower edge forms an arch across the face of the lamp. In this way the upper rays of the light are prevented from hindering the sight of persons approaching the vehicle and still a simple and effective shield is provided which may be easily and quickly swung into its lowered position to permit the user to get the full benefit of the light.

While in the foregoing there has been shown and described the preferred embodiment of this invention, it is to be understood that such changes may be made in the combi-

nation and arrangement of parts as will fall within the spirit and scope of the invention as defined in the appended claim.

Having thus described my invention, I claim:

The combination with an automobile headlight, of a shield formed of a single piece of metal, the inner edge thereof being concentric with and adapted to fit within the outer front flange of the headlight, the outer edge thereof and the adjacent portion on

either side being extended to form supporting arms pivotally attached to the outside of the headlight casing, one of said arms being extended to form a lever, and an operating rod pivotally connected with the lever. 15

In testimony whereof I affix my signature in presence of two witnesses.

ALBERT C. KAUFMANN.
